Des. 185,197
Patented May 19, 1959

185,197

COMBINED COOKING AND SERVING UNIT FOR SOUP OR THE LIKE

Gilbert C. Gettelman, Whitefish Bay, Wis., assignor to Geuder, Paeschke & Frey Co., Milwaukee, Wis., a corporation of Wisconsin

Application July 28, 1958, Serial No. 51,960

Term of patent 3½ years

(Cl. D81—10)

Fig. 1

Des 185,197

PAGE 2

Fig. 3

Fig. 1 is a view in front elevation of a combined cooking and serving unit for soup or the like embodying my new design;

Fig. 2 is a top plan view;

Fig. 3 is a view in end elevation thereof, the opposite end being substantially the same in appearance.

The rear of the cooking element and base element is plain.

I claim:

The ornamental design for a combined cooking and serving unit for soup or the like, substantially as shown and described.
